[57] ABSTRACT

A conveyor system has a cross-feed conveyor for moving stacks of cases to an accumulating area, and an in-feed transfer system for selectively feeding the stacks.

onto respective live storage conveyors in the accumulating area. Each live storage conveyor includes a track for supporting the stacks of cases, longitudinally spaced apart engaging lugs pivotally mounted on a reciprocating carriage centered in each track, and respective sensing members for sensing the presence of stacks located on the track and for urging the lugs into contact with the stacks of cases located forward of the engaging lugs. Each forward stroke of the carriage pushes the engaging lugs against the stacks to move the stacks forward along the conveyor track. The sensing members are positioned forward of their respective engaging lugs, and each sensing member is depressed by a stack positioned on the carriage above it to break contact between the sensing member and its respective lug. This causes the lug to drop under gravity to an inoperative position so the lug will not move a stack forward on the track when there is no unoccupied space for receiving it. The engaging lug at the end of each conveyor track is normally maintained in an inoperative position while stacks are being accumulated on the track. A slideable bar moves a separate lug lifting member into engagement with each lug to move all lugs into an operative raised position when it is desired to override the instructions of the sensing members and discharge the accumulated stacks, one-by-one, onto an out-feed conveyor leading from the accumulating area to a shipping area.

LIVE STORAGE CONVEYOR SYSTEM**CROSS-REFERENCE TO RELATED APPLICATION**

This is a continuation-in-part of my copending application Ser. No. 35,020, filed May 6, 1970, now abandoned.

BACKGROUND OF THE INVENTION**1. Field of the Invention**

This invention relates to conveyors, and more particularly to a conveyor system which includes an improved live storage conveyor for moving stacks of cases or the like into close proximity to each other on a storage track.

2. Description of the Prior Art

Dairy plants and similar operations where products are packaged in containers, such as milk or cottage cheese cartons, are concerned with efficient and economical distribution of the goods after production. In most packaging or bottling plants, assorted cartons are initially placed in cases for shipment by truck to grocery stores or directly to the consumer. After the cartons are filled and placed in the cases, problems often arise in selecting and moving the cases from the storage area to the truck loading area. Shipment orders almost always call for loads containing an assortment of products. Thus, cases from one production line must be combined with a desired number of cases from other production lines in the plant. For example, cartons of dairy products are taken from filling machines and placed in respective cases which are then stacked in a stacking machine. Similarly, cases of cottage cheese are received from another production line and stacked. When a shipment order is received for a load which includes an assortment of products, the order is "picked" and stacks of cases of each product are moved together to the loading area.

At present, stacks of cases of different products are usually conveyed by conventional chain conveyors to a storage area where they are manually pulled from the conveyor and dragged over steel floors for storage. This system requires considerable manpower to produce a continuous flow of goods both to and from the conveyors. Moreover, delays are frequently caused because stacks of various goods are often located at quite a distance from the conveyors. Movement of cases in this fashion also requires considerable supervision, and has been seriously lacking in inventory control.

It is recognized that the flow of goods through packaging or bottling plants could be substantially improved if there were available a relatively simple powered automatic system for continuously moving stacks of cases from a production area onto desired storage tracks so that the cases could be automatically accumulated in rows of like products. Such a system would also preferably include means for automatically advancing stacks of products to a picking line as each preceding stack is moved onto a conveyor for shipment.

SUMMARY OF THE INVENTION

This invention provides a conveyor system which includes an improved live storage conveyor for automatically accumulating stacks of cases on a storage track. The system also includes an automatic in-feed transfer mechanism for selectively moving stacks of cases onto respective side-by-side live storage conveyors. The sys-

tem requires limited manpower and supervision to quickly separate stacks of goods and transfer them from an accumulating area to a shipping area. Furthermore, the structure and operation of the live storage conveyor is relatively simple, and no accumulated pressure is exerted on the conveyor track as stacks accumulate along the track. Consequently, the system is economically suitable for use in most packaging or bottling plants which handle numbers of assorted cases or the like.

Briefly, the live storage conveyor includes a reciprocating carriage which cooperates with a track to move objects forwardly along the track. An engaging lug mounted on the carriage pivots from an operative position, in which the lug contacts the bottoms of objects disposed over the conveyor track, to an inoperative position, in which the upper surface portion is out of contact with the objects. A sensing member secured to the carriage forward of the engaging lug is normally operative to contact the engaging lug to urge the lug into its operative raised position. The sensing member is adapted to move downwardly when contacted by an object disposed on the track above it, so that the lug drops under gravity to its inoperative position. In use, when the lug is in its raised position, a forward stroke of the carriage causes the engaging lug to force objects forwardly along the track. The sensing member prevents the lug from moving an object forward unless there is a space into which the object can be moved.

In its preferred form, the engaging lug includes a substantially vertical engaging surface portion adapted to contact the bottom of milk cases, or other objects, disposed on the conveyor tracks. The sensing member is held in pressure contact with the lug to raise the engaging surface portion of the lug into an operative position in which it will contact objects on the conveyor track. The engaging lug is arranged to pivot relative to the conveyor carriage so it freely drops under gravity to an inoperative position when the sensing member is moved out of pressure contact with the lug. A nose portion of the lug limits pivotal movement of the lug by resting on the bottom of the conveyor carriage when the lug pivots to its inoperative position. This prevents the rear portion of the lug from striking objects disposed on the conveyor carriage above it on the return stroke of the carriage. The preferred form of the invention further includes stop means disposed below the engaging lug for limiting pivotal movement of the lug away from the direction in which objects are conveyed.

The sensing member preferably comprises a longitudinally extending continuous arm having a forward portion normally held above the conveyor track so as to sense objects positioned on the track above it. The sensing member also has a rear portion located so it moves into and out of pressure contact with the engaging lug. When the forward portion of the sensing member is above the conveyor track, the rear portion of the sensing member is held in pressure contact with the engaging lug to raise the lug to its operative position. When the forward portion of the sensing member is contacted by an object on the track, it moves downwardly to move the rear portion of the member out of pressure contact with the lug. This allows the lug to pivot to its inoperative position so an object will not be pushed against the object sensed by the sensing member.

The preferred form of the live storage conveyor includes selective control means for intermittently or continuously reciprocating the carriage so as to move a series of objects along the conveyor track. The engaging lug at the end of the track is normally maintained in an inoperative position as the carriage reciprocates so as to prevent the objects from being discharged from the track. Thus, as the carriage reciprocates, objects are accumulated along the track, with each object almost touching the object in front of it on the track. As the objects accumulate, no pressure is exerted from one stack to the next, so there is no accumulated pressure along the entire length of the conveyor track.

The preferred form of the conveyor carriage includes a carrier bar adapted to move back and forth relative to the engaging lug, and a lug position control member secured to the carrier bar and arranged to override the effect of the sensing member and maintain the lug in its operative position when the carrier bar is moved to a predetermined position relative to the lug. An out-feed conveyor is preferably located at the end of the live storage conveyor, and accumulated objects on the conveyor track are discharged onto the out-feed conveyor by moving the carrier bar to its predetermined position and then continuously reciprocating the conveyor carriage.

The preferred form of the live storage conveyor includes a pair of parallel rails for supporting objects to be conveyed, and a pair of parallel, elongated conveyor carriages disposed in cooperative relation with the rails. The conveyor carriages include elongated channel members adapted to move relative to the storage track. A plurality of longitudinally spaced engaging lugs are pivotally mounted within each channel member and spaced from each other by a distance slightly greater than the length of the objects conveyed. A separate sensing member is mounted forward of each engaging lug. Drive means reciprocate the channel members relative to the conveyor track, and as the channel members move during a forward stroke, only the engaging lugs selectively disposed in an operative position force stacks forwardly along the conveyor track. The forwardly moved stacks depress the sensing members corresponding to the engaging lugs positioned behind the stacks, so that these lugs pivot to an inoperative position which prevents the lugs from moving a stack forward when there is no empty space for receiving the stack.

In a preferred form of the conveyor system which is particularly useful in a dairy plant or the like, stacks of cases from a plurality of casing and stacking machines are conveyed to a cold storage area on a single chain conveyor. Upon arrival in the cold storage area the stacks are fed by a cross-feed conveyor to an accumulating area having side-by-side rows of live storage conveyors. A preferred cross-feed conveyor includes an elongated conveyor track for supporting objects to be conveyed, and a reciprocating carriage centered in the track. A series of engaging lugs mounted on the carriage pivot from an operative position contacting the bottoms of objects disposed on the track to an inoperative position out of contact with the objects. Longitudinally spaced apart lug position control members below the engaging lugs maintain the lugs in their operative positions so they force objects forwardly along the track as the carriage makes a forward stroke. Lug stop means below the lugs prevent the lugs from pivoting

away from the direction in which objects are conveyed. The lug stop means and control members preferably are carried by a slideable carrier bar adapted to move relative to the lugs. At the end of each forward stroke, carrier bar stop means move the carrier bar relative to the lugs to move the control members out of contact with the lugs to allow the lugs to pivot to their inoperative positions for the return stroke of the carriage.

An in-feed transfer system selectively moves stacks containing one type of product from the cross-feed conveyor onto the desired one of the live storage conveyor tracks. The stacked cases on the various live storage conveyors are progressively moved toward the discharge end of their respective conveyor tracks and automatically accumulated as explained above. Thus, each track can be completely filled with stacks containing a particular product. Sensing means sense when a conveyor track is completely filled so as to activate disabling means for preventing the in-feed transfer system from further pushing additional stacks of cases onto the conveyor track. When orders are received for a shipment containing a load of assorted products from the different live storage conveyors, the carrier bars in each row are moved to their predetermined position and the respective live storage conveyor carriages are reciprocated, one conveyor at a time, to discharge the desired number of cases from each conveyor track onto the out-feed conveyor. The shipment load is moved from the accumulating area by the out-feed conveyor to a shipping area where it is loaded onto trucks.

BRIEF DESCRIPTION OF THE DRAWINGS

These and other aspects of the invention will be more fully understood from the following detailed description and the accompanying drawings, in which:

FIG. 1 is a plan view of the conveyor system of this invention;

FIG. 2 is a sectional end elevation of the live storage conveyor taken on line 2-2 of FIG. 1;

FIG. 3 is an enlarged sectional end elevation of the apparatus within the circle 3 of FIG. 2;

FIG. 4 is a sectional side elevation taken on line 4-4 of FIG. 3;

FIG. 5 is a plan elevation taken on line 5-5 of FIG. 4;

FIG. 6 is a sectional end elevation of an alternative embodiment of the apparatus of FIG. 2;

FIG. 7 is a sectional side elevation of an alternative control spring;

FIG. 8 is a schematic side elevation showing stacks of cases positioned on a conveyor track during operation of the sensing and engaging mechanism;

FIG. 9 is a schematic side elevation showing stacks of cases accumulated in accumulated position on the storage track;

FIG. 10 is a schematic side elevation showing the operation of the control springs on the carrier bar;

FIG. 11 is a schematic side elevation showing means for discharging stacks of cases from the live storage conveyor onto an out-feed conveyor;

FIG. 12 is a sectional side elevation of an alternative control spring and engaging lug combination;

FIG. 13 is a schematic side elevation showing an alternative means of positioning the engaging lug at the end of the conveyor;

FIG. 14 is a schematic side elevation showing the operation of the system of FIG. 13 when discharging a stack of cases onto an out-feed conveyor;

FIG. 15 is a schematic side elevation of a preferred cross-feed conveyor;

FIG. 16 is a schematic side elevation showing means for positioning a slidable lug control spring carrier bar used in the cross-feed conveyor;

FIG. 17 is a plan elevation of the conveyor system showing an in-feed transfer system for moving stacks of cases from the cross-feed conveyor onto the live storage conveyor track positioned between the cross-feed conveyor and the out-feed conveyor;

FIG. 18 is a schematic circuit diagram illustrating the operation of the system shown in FIG. 17;

FIG. 19 is an enlarged side elevation of the control spring carrier bar actuator taken on line 19-19 of FIG. 17;

FIG. 20 is a side elevation of the apparatus of FIG. 19 shown in its forward position;

FIG. 21 is a sectional end elevation of an alternative conveyor track;

FIG. 22 is a sectional end elevation of an alternative conveyor carriage;

FIG. 23 is a perspective view of an alternative lug control spring and a spring holder and mounting block;

FIG. 24 is a plan elevation taken on line 24-24 of FIG. 23;

FIG. 25 is a side elevation taken on line 25-25 of FIG. 24;

FIG. 26 is a perspective view of an alternative spring holder and mounting block;

FIG. 27 is a perspective view of a pivot pin retainer clip;

FIG. 28 is a side elevation showing the retainer clip of FIG. 27 in use;

FIG. 29 is a side elevation of an alternative pivot pin retainer clip;

FIG. 30 is a perspective view showing an engaging lug with a special insert for moving cases having no bottom rim;

FIG. 31 is a perspective view of an alternative engaging lug insert;

FIG. 32 is a fragmentary sectional elevation showing a presently preferred embodiment of the sensing and engaging mechanism for the live storage conveyor;

FIG. 33 is a plan elevation showing a sheet metal stamping for use in forming the engaging lug to be used in the sensing and engaging mechanism of FIG. 32;

FIG. 34 is a fragmentary sectional side elevation of the live storage conveyor incorporating the sensing and engaging mechanism of FIG. 32;

FIG. 35 is a fragmentary plan elevation taken on line 35-35 of FIG. 34;

FIG. 36 is a fragmentary sectional elevation showing an out-feed conveyor at the discharge end of the live storage conveyor of FIG. 32;

FIG. 37 is a fragmentary sectional elevation showing an in-feed conveyor at the entry side of the live storage conveyor of FIG. 32 and a transfer mechanism for moving objects from the in-feed conveyor onto the live storage conveyor;

FIG. 38 is a fragmentary plan elevation taken on line 38-38 of FIG. 37;

FIG. 39 is a fragmentary elevation showing an alternate position of the transfer mechanism shown in FIG. 37;

FIG. 40 is an elevation showing an alternate embodiment of a torsion spring for use in raising the engaging lugs;

FIG. 41 is an elevation taken on line 41-41 of FIG. 40;

FIG. 42 is a fragmentary elevation showing a presently preferred method of mounting the engaging lugs on the reciprocating carriage; and

FIG. 43 is a sectional elevation taken on line 43-43 of FIG. 42.

DESCRIPTION OF THE PREFERRED EMBODIMENTS

Referring to FIG. 1, a conveyor system 30 adapted for use in a dairy products plant conveys cases 32 of dairy products from a series of production lines 34 through an accumulating area 36 to a shipping area 38 where the cases are loaded onto trucks 40. A number of stacking machines in a stacking area 42 are located at the end of a production area 44 for receiving dairy products from production lines 34. Stacks of cases 32 are fed from the stacking machines on conventional chain belt conveyors 46 to an in-feed conveyor 48 for moving the stacks of cases from the stacking machines onto a cross-feed conveyor 49 which delivers the stacks to the accumulating area 36. A plurality of side-by-side live storage conveyors 50 are disposed perpendicularly to the cross-feed conveyor 49 in the accumulating area 36, and each stack of cases on the cross-feed conveyor is moved onto a desired one of the live storage conveyors 50 by an indexing system described below. When orders for a shipment lot are received, cases are moved from the appropriate live storage conveyors onto an out-feed conveyor 52 at the discharge end of the accumulating area 36. The out-feed conveyor moves the shipment lot to the shipping area 38 where the cases are moved onto the trucks 40.

Referring to FIGS. 2 through 5, the live storage conveyors 50 include a plurality of longitudinally spaced apart track supports 54 spaced at intervals from the cross-feed conveyor 49 to the out-feed conveyor 52. The track supports 54 are supported above the floor 56 of the accumulating area 36 by upright support legs 58. Each track support 54 supports an elongated rail 60 which in transverse cross-section defines a separate upwardly opening outer channel member 62 extending along each edge of the track support, and a separate horizontally disposed platform 64 positioned adjacent to and above each outer channel member 62. An elongated wear strip 66 is mounted on each platform 64, and adjacent pairs of wear strips 66 provide separate storage tracks or conveyor tracks 68 for supporting stacks of cases 32, as seen best in FIG. 2.

Each conveyor track 68 has a respective pair of adjacent outer channel members 62, and a separate elongated reciprocating carriage 70 running the length of each conveyor track 68 is disposed within each pair of outer channel members 62. Each reciprocating carriage 70 supports a respective sensing and engaging mechanism 72 which moves in and out of engagement with stacks of cases 32 so as to move the stacks forwardly along its respective conveyor track. As seen best in FIG. 3, each conveyor carriage 70 includes an upwardly opening channel member 74 slidably

mounted on an elongated wear strip 76 disposed within each outer channel member 62. Channel member 74 runs substantially the length of the conveyor track and is connected to reciprocating drive means described below for moving it relative to the conveyor track 68.

A downwardly extending rim 78 circumscribes the bottom of each case 32, and the bottom of the rim rests on the conveyor track 68. The sensing and engaging mechanism 72 includes a plurality of longitudinally spaced engaging lugs 80 pivotally mounted on each slidable channel member 74 by respective transverse pivot pins 82. Each pair of laterally spaced apart engaging lugs 80 is arranged to engage a respective portion of the front lip 78 at the bottom of each case 32, and as the slidable channel member 74 reciprocates, the lugs pull the cases forwardly along the storage track 68. A separate vertically disposed wear strip 84 supported from each side of the rail 60 extends along a respective outer edge of the storage track 68 to provide means for guiding the cases along the conveyor track.

As seen best in FIG. 4, each engaging lug 80 has a vertically disposed upper surface portion 86 on its front side, and a forwardly projecting nose 88 below the vertical surface 86. Preferably, the engaging lug 80 is constructed of plastic, and the vertical surface 86 is defined by a metal tooth secured to the front of the lug. A separate elongated sensing spring 90 is secured to the slidable channel member 74 forward of each engaging lug 80. The sensing springs preferably comprise a pair of parallel, elongated torsion springs in the form of wire segments 92 curved concave upwardly above the upper surface of conveyor track 68. A transverse lug support member 94 formed integrally with the rear ends of the wire segments 92 engages the lower surface 96 of the nose 88 of engaging lug 80 so as to maintain the lug in a normally operative position shown in solid lines in FIG. 4. A separate transverse support member 98 extends between the side walls of slidable channel member 74 forward of each sensing spring 90, and the forward ends of the sensing spring wire segments 92 are looped in a coil and locked in respective holes 100 extending through the support member 98.

Referring to FIG. 4, a lug control spring 101 preferably comprises a horizontally disposed, forwardly projecting leaf spring 102 secured to the top of a separate mounting blocks 104 located below the rear portion of each engaging lug 80. The mounting blocks are fixed to a slidable elongated control spring carrier bar 106 disposed within slidable channel member 74. Each carrier bar 106 is connected to actuating means described in detail below for sliding it between a forward position and a retracted position relative to its respective channel member 74. Thus, the lug control springs 101 of each carrier bar 106 move relative to their respective engaging lugs 80. FIG. 4 shows the carrier bar 106 in its retracted position in which an upwardly projecting transverse ridge 108 adjacent to the forward end of each lug control spring 101 is positioned slightly to the rear of the pivot point of its corresponding engaging lug 80.

During use of the sensing and engaging mechanism 72, a stack of cases 32 is moved forwardly along conveyor track 68 substantially one case width each time the reciprocating channel members 74 of the conveyor carriage 70 make a forward stroke in the direction of the arrow shown in FIG. 4. During forward movement

of each channel member, the sensing spring 90 maintains the engaging lug 80 in its operative position so that the vertical contacting surface 86 is forced against the rim 78 at the front of a case 32 located at the bottom of the stack so as to move the stack forward. The mounting block 104 provides a stop for the rear portion of the lug to prevent the lug from pivoting in a counter-clockwise direction away from the rim of the case during forward movement of the slidable channel member 74. After completing a forward stroke, the channel member returns to its initial position, with the moved stack of cases 32 positioned immediately forward of the engaging lug 80, as shown in phantom lines in FIG. 4. In this position the stack of cases compresses the sensing spring 90 as shown in phantom lines to permit the engaging lug to pivot under gravity and the upward force of spring 102 to an inoperative position also shown in phantom lines. When the engaging lug is maintained in its inoperative position, further reciprocal movement of the slidable channel member 74 fails to move a trailing stack of cases against the stack of cases positioned immediately forward of the lug. The nose 88 of the engaging lug 80 is configured so that it rests against the upper surface of the control spring carrier bar 106 when the lug pivots to its inoperative position. This provides a stop for preventing further pivotal movement of the lug in a clockwise direction, so that the rear portion of the lug does not strike the cases on the conveyor track 68 during the return stroke of the slidable channel member 74.

FIG. 6 shows alternative means for mounting the conveyor track and conveyor carriage above the floor of the accumulating areas 36. In this form of the invention, an elongated support plate 110 extends between the cross-feed conveyor and the out-feed conveyor. The plate is secured to the top of legs 114, and has a pair of relatively short upright side walls 115 spanning its outer edges. A pair of parallel rails 116, preferably made of square tubing, rest on a central portion of the plate 110 and extend substantially the entire length of the plate 110. The rails 116 are maintained in a fixed parallel relation by a downwardly opening elongated channel member 118 having a pair of side walls 120 welded to the adjacent inner side walls of the rails. A separate, elongated wear strip 122 is secured to the top of each rail 116, and the cases rest on the wear strip as they move forwardly along the conveyor track. A second elongated wear strip 124 is secured to the outside of each side wall 120 to provide means for guiding the cases along the conveyor track. A separate conveyor carriage 70 and its respective sensing and engaging mechanism 72 are slidably mounted on a respective elongated wear strip 126 disposed between the outer side wall of each rail 116 and its adjacent outer side wall 112 of plate 110. The spacing A between the upper surface of wear strip 122 and the pivot point of the engaging lug 80, and the spacing B between the side walls 120 of channel member 118 must both be maintained within relatively narrow tolerances for the live storage conveyor 50 to operate effectively. The form of the invention shown in FIG. 6 is preferred because the rails 116 and channel members 118 are formed from structural components of standard sizes. This facilitates maintaining the dimensions A and B within relatively close tolerances.

FIG. 7 shows an alternative lug control spring 130 secured to control spring carrier bar 106. The lug control

spring 130 comprises an upwardly projecting leaf spring 132 having an upper lug-contacting surface 134 positioned slightly to the rear of the pivot point of the engaging lug 80 when the carrier bar 106 is in its retracted position. A flat rear portion 135 of the control spring 130 rests on the upper surface of the control spring carrier bar 106, and a stop 136 for the rear portion of the engaging lug is mounted on the rear portion of the control spring. The stop 136 and control spring 130 are secured to the carrier bar 106 by a pair of screws 138.

Referring to FIG. 8, live storage conveyor 50 is shown in use moving stacks of cases 32 forwardly along the conveyor track 68 in the direction of the arrow. During this forward movement of the cases, the control spring carrier bar 106 is maintained in its retracted position, so that the engaging lugs 80 operate under the control of the sensing springs 90. The engaging lugs 80 are longitudinally spaced by a distance slightly greater than the width of the cases 32, and during each forward stroke of the slidable channel member 74 the engaging lugs move their respective stacks forwardly a distance substantially equal to the longitudinal spacing between the engaging lugs. Thus, after the return stroke of the channel member, each forwardly moved stack is positioned immediately in front of the next engaging lug. Continuous reciprocating movement of the slidable channel member 74 moves the stacks along the conveyor track 68 in a spaced apart relation, as shown in FIG. 8. This movement of the stacks is produced because engaging lugs 80 pivot to their inoperative positions after the slidable channel member 74 moves to its retracted position if cases 32 are positioned so as to depress their respective sensing springs 90 and thereby cause their corresponding lugs 80 to rotate to their inoperative positions. Thus, a given stack is engaged and moved forward only if there is an empty space ahead of its respective engaging lug for receiving the stack.

The engaging lugs at the end of each conveyor track 68 (labeled A in FIGS. 8 through 11) have no cooperating sensing springs. Since the control spring carrier bar 106 is maintained in its retracted position during forward movement of the cases, as shown in FIG. 8, the engaging lugs A are maintained in an inoperative position. This prevents engaging lugs A from discharging the leading stack of cases (Stack No. 1 in FIGS. 8 through 11) beyond the end of the conveyor track. After the leading stack has reached a position immediately in front of engaging lugs A, as shown in FIG. 8, further feeding of stacks onto the conveyor track combined with continued reciprocating movement of the slidable channel member 74 causes the stacks to accumulate in a side-by-side relation, as shown in FIG. 9, until the conveyor track is completely filled. The conveyor 50 permits incoming stacks of cases to be accumulated in the accumulating area 36, because the sensing springs 90 instruct the engaging lugs when and when not to move the stacks forward along the conveyor track.

The stacks of cases 32 accumulated on conveyor track 68 of the live storage conveyor 50 can be discharged from the conveyor track onto the out-feed conveyor 52 when desired. FIGS. 10 and 11 show a preferred system for discharging the leading stack of cases (Stack No. 1) onto out-feed conveyor 52. Control spring carrier bar 106 is moved in the direction of the arrow shown in FIG. 10 to a forward position so as

to move the lug control springs 101 forward relative to their respective engaging lugs 80. When the control spring carrier bar 106 is in its forward position, the control springs are held in contact with the bottoms of their respective engaging lugs, and the ridge 108 adjacent to the front end of each control spring 101 is positioned forward of the pivot of its respective engaging lug. This movement of the carrier bar 106 overrides the effect of the sensing springs 90 and maintains the engaging lugs fixed in their operative positions. To discharge a stack of cases onto out-feed conveyor 52, slidable channel member 74 is then reciprocated so as to force engaging lugs A in a forward direction against the rim 78 at the rear of the No. 1 stack shown in FIGS. 10 and 11. This movement of the channel member 74 forces the No. 1 stack off the end of conveyor track 68 and onto out-feed conveyor 52, as seen in FIG. 11. Also, each lug 80 engages the rim 78 of its respective case to move the remaining cases forward one space for each forward reciprocation of the channel member 74. As the channel member 74 moves back during its return stroke, the engaging lugs 80 pivot downward against their respective lug control springs 101 when contacting the bottoms of the cases disposed over the conveyor track. At the completion of the return stroke, each succeeding stack of cases has moved up one position, with Stack No. 2 being at the end of the conveyor track. Further reciprocating movement of the channel member 74 discharges the remaining stacks one at a time. After the desired number of cases are discharged, the control spring carrier bar 106 is retracted to permit the engaging lugs to operate under the control of the sensing springs. Thus, more stacks of cases can be fed onto the conveyor track to replace the discharged stacks and accumulated in side-by-side relation until the track is again full.

The engaging lugs shown in FIGS. 8 through 11 are arranged such that the spacing between lugs A and B is slightly greater than the spacing between the remaining lugs. Thus, engaging lugs A are forced against the rim 78 at the rear of the No. 1 stack, and engaging lugs B are forced against the rim at the front of Stack No. 3, etc. thereby moving Stacks No. 1, No. 2, and No. 3, etc. simultaneously during the forward stroke of channel member 74.

FIG. 12 shows a typical engaging lug 80 in combination with an alternative lug control spring 140 having an upwardly curved rear portion 142 between mounting block 104 and the lower surface at the rear of the lug. This form of the control spring is particularly useful in combination with engaging lugs B, which are required to move two stacks of cases simultaneously during discharge operations, as described above. In use, the rear portion 142 of the control spring is compressed slightly when Stack No. 3 is forced against Stack No. 2, so that the contacting surface 86 of engaging lug B is rotated upward a slight amount. This movement of the lug assures that the contacting surface 86 of the lugs B securely grip the lip of the bottom case. A sharp tooth 144 can be formed at the upper edge of the contacting surface 86 to provide further means for digging into the lip of the case. It has been found, however, that the engaging lug and control spring combination shown in FIG. 4 effectively moves two stacks forward simultaneously when the angle α between the horizontal plane and a line from the pivot point of the lug through the upper edge of the contacting surface 86 is 45° or

slightly greater than 45°. This configuration permits the lug to rotate upward slightly and dig into the inside of the lip at the front of the case when Stack No. 3 is forced against Stack No. 2.

FIGS. 13 and 14 show an alternative arrangement of the engaging lugs 80 in which the spacing between engaging lugs A and engaging lugs B is substantially less than the spacing between the remaining lugs. In this form of the invention, the lugs 80 engage the rims of the cases so that it is not necessary for the lugs C to push Stack No. 3 into Stack No. 2 and move both stacks. A stack of cases at the end of the conveyor track is discharged onto out-feed conveyor 52 as engaging lugs A are forced against the rim 78 at the rear of the bottom case. Each of the remaining engaging lugs pulls one respective stack forward one position during the forward stroke of the channel member 74. However, in this form of the invention, the spacing between the stack on the out-feed conveyor and the end of the rails of conveyor 50 is less than that of the conveyor shown in FIGS. 10 and 11, so there is less passing clearance for stacks moving on the out-feed conveyor.

The operation of the cross-feed conveyor 49 is best understood by referring to FIGS. 15 and 16. The cross-feed conveyor preferably includes a laterally extending conveyor track 160 at the front of the side-by-side live storage conveyors 50. A reciprocating conveyor carriage 162 disposed inside conveyor track 160 includes an elongated slidable channel member 164 which supports a plurality of pivotally mounted engaging lugs 166. Preferably, each engaging lug 166 has a vertical upper surface portion that extends upwardly higher than vertical surface 86 of engaging lugs 80. This configuration permits each lug to contact the rear wall of a case instead of the rear lip of the case. The engaging lugs 166 are normally maintained in an operative position by a respective lug control spring 168 secured to a mounting block 170 fixed to a slidable control spring carrier bar 172. The engaging lugs 166 are spaced so that during use of the cross-feed conveyor 49, the vertical contacting surfaces of the lugs push the cases forwardly along the conveyor track 160. Thus, stacks of cases 32 are moved along the track one position in the direction of the arrow shown in FIG. 15 each time channel member 164 reciprocates. Since the engaging lugs 165 are not under the control of sensing springs, such as the previously described sensing springs 90, the stacks can be moved along the conveyor track in an end-to-end relation.

Control spring carrier bar 172 is preferably slightly longer than channel member 164, as shown in FIG. 16. An adjustable stop 174 is located adjacent to the rear end of the cross-feed conveyor 49, and a similar adjustable stop 175 is located adjacent to the front of the cross-feed conveyor. Stops 174 and 175 have respective adjustable pins 176 and 177 arranged to contact a respective outwardly extending portion of the control spring carrier bar 172 as the carrier bar reciprocates. Thus, at the end of the forward stroke of the channel member 164, the end of the carrier bar 172 is forced against pin 176 of stop 174 to slide the carrier bar and the lug control springs 168 back away from their respective engaging lugs 166, so that the lugs pivot to their inoperative positions, shown at the left side of FIG. 16. At the end of the return stroke of the channel member 164, the front portion of the carrier bar 172

is projecting outwardly and contacts the pin 177 of stop 175. This slides the carrier bar forward relative to the engaging lugs to raise the lugs to their operative positions shown at the right side of FIG. 16. In use, during each return stroke of the cross-feed conveyor, the engaging lugs 166 are maintained in an inoperative position below the level of the conveyor track 160, so that they avoid striking a stack of cases fed from in-feed conveyor 48 (see FIG. 1) onto the cross-feed conveyor track.

Cross-feed conveyor carriage 162 is driven back and forth by a hydraulic cross-feed cylinder (not shown) adapted to move an outwardly extending reciprocating piston rod (not shown) coupled to slidable channel member 164. When the cross-feed conveyor carriage reaches its forward position, a triggering device 178 adjacent to the end of the cross-feed conveyor track 160 is actuated to energize a solenoid valve coil, described below in detail, of the cross-feed actuator carriage to retract the actuator piston rod to move the cross-feed conveyor carriage to its returned position. When the cross-feed conveyor reaches its returned position, a triggering device 180 located to the rear of triggering device 178 is actuated to energize a different solenoid valve coil, described below in detail, which is adapted to move the cross-feed actuator piston rod forward after a predetermined time delay.

The operation of the conveyor system of this invention is best understood by referring to FIGS. 17 through 21. Each stack of cases 32 is fed from the cross-feed conveyor 49 onto a respective one of the live storage conveyors 50 by an in-feed transfer mechanism which includes an indexing system comprising a separate photo-electric cell 182 positioned above the cross-feed conveyor 49 forward of each live storage conveyor 50. In use, the indexing system preferably operates in a manner similar to the conventional card-reader. Each stack of cases is provided with a code-bearing card (not shown) or the like which corresponds to a particular product contained within the cases, and each photo-electrical cell is activated in response to the presence of a different predetermined code card placed in the top case of the stack before it leaves the stacking machine. The stacks pass under the photo-electric cells 182 during their movement along the cross-feed conveyor 49, and at the completion of each forward stroke of the cross-feed conveyor carriage 162, each stack of cases on the cross-feed conveyor is directly in line with the in-feed end of a live storage conveyor 50, as shown in FIG. 17. When a stack of cases is moved past the code card reader 182 for the lane in which its respective product is to be accumulated, the photo-electric cell 182 corresponding to that lane is activated by the code card in the top case. A separate double-acting hydraulic stack transfer cylinder 184 at the front of each lane has an outwardly extending reciprocating push-rod 186 and a solenoid valve coil, described in detail below, for moving the push-rod 186 to a forward position when energized. Each solenoid valve coil is energized if its respective photo-electric cell 182 is activated, but only after the cross-feed conveyor has completed a forward stroke, thus positioning the stacks directly in line with the in-feed end of the live storage conveyor, so that when each push-rod 186 moves to its forward position, it pushes a stack of cases from the cross-feed conveyor onto a corresponding live storage conveyor lane. For example, FIG. 17 shows the hydrau-

lic stack transfer cylinder 184 corresponding to a live storage conveyor lane C pushing a stack of cases in the direction of the arrow onto lane C in response to activation of the photo-electric cell 182 corresponding to lane C. When the stack is pushed onto the conveyor track of lane C, the rim of the case comes to rest in front of the first pair of engaging lugs on the conveyor carriage of lane C. Reciprocating movement of the conveyor carriage 70 then pulls the stack completely onto the conveyor track.

A separate limit switch 3-LS is located at the in-feed of each live storage conveyor lane, and when a stack of cases is transferred from the cross-feed conveyor 49 onto the in-feed portion of a respective one of the lanes, the bottom case contacts the lane's corresponding limit switch 3-LS. A separate hydraulic indexing cylinder 190 disposed within each lane of the live storage conveyors 50 has a respective solenoid valve coil, described in detail below, which is energized when a corresponding one of the limit switches 3-LS is actuated. Each indexing cylinder 190 has a respective outwardly extending reciprocating piston rod 192 and a corresponding laterally disposed tie-bar 194 secured to the end of the piston rod and coupled at its ends to slid-able channel member 74 of a respective conveyor carriage 70. The piston rod 194 of each indexing cylinder 190 is adapted to move between a forward position (shown in phantom lines in FIG. 17) and a retracted position (shown in solid lines in FIG. 17) when each solenoid valve coil of the respective indexing cylinders is energized. Each limit switch 3-LS is adapted to energize a solenoid valve coil of a corresponding indexing cylinder when actuated, and in use, when a stack of cases is pushed onto the in-feed end of a live storage conveyor lane, it actuates a respective limit switch 3-LS to move a corresponding piston rod 194 to its forward position. This movement forces the conveyor carriage 70 forward so that the engaging lugs 80 at the in-feed end of the lane pull the stack forward onto the conveyor track 68. Each succeeding transfer of a stack onto the conveyor track is followed by two respective reciprocal movements of the indexing cylinder.

After stacks are accumulated in a side-by-side relation at the end of the conveyor track, they may be stored or discharged one at a time onto the out-feed conveyor 52. The discharge mechanism includes a separate air cylinder or control spring carrier cylinder 200 mounted within each slid-able channel member 74 adjacent to the end of each conveyor track. Each air cylinder 200 has an outwardly extending reciprocating piston rod 202, and the forward end of each piston rod is secured to a corresponding control spring carrier bar 106, as shown best in FIGS. 19 and 20. In use, when it is desired to discharge the stacks onto out-feed conveyor 52, a respective control switch, described in detail below, on a control panel (not shown) is closed. Each air cylinder 200 has a respective solenoid valve coil, described in detail below, which is energized when the control switch is closed so as to move the piston rod 202 to a forward position shown in FIG. 20. This movement of the piston rod slides the control spring carrier bar 106 to its forward position so that lug control springs 101 raise their respective engaging lugs 80 to their operative positions. Continuous reciprocal movement of the indexing cylinder 190 thereafter discharges the stacks.

A separate limit switch 4-LS positioned at the end of each conveyor track 68 is actuated by any stack which has moved to the end position of the track. Each limit switch 4-LS is adapted to cooperate with its respective limit switch 3-LS at the in-feed end of the conveyor track 30 as to sense when the track is filled with stacks of cases to prevent the transfer cylinder 184 from pushing additional stacks of cases onto the conveyor track. The limit switch 4-LS also energizes a different solenoid valve coil, described in detail below, of each air cylinder 200 to move the respective piston rods 202 to a retracted position shown in FIG. 19, thereby moving the control spring carrier bar 106 back so the sensing springs 90 are in charge of the position of lugs 80.

Thus, the stacks are automatically accumulated on the conveyor track without pushing one stack against another, and with no pressure accumulated along the entire length of the conveyor track. The electrical system for automatically controlling the operation of the conveyor system of this invention is best understood by referring to FIG. 18. A limit switch 1-LS is closed at the end of the forward stroke of the channel member 164 to thereby energize a coil 12 of a first control relay 1-CR. A normally open contact 214 of control relay 1-CR is closed when the control relay coil 212 is energized to supply power to a solenoid valve coil 216 of the cross-feed cylinder (not shown in FIG. 18). This moves the piston rod (not shown) of the cross-feed cylinder from its forward position to its rear position to provide a return stroke of the cross-feed conveyor carriage 162.

If a stack of cases is not transferred from the cross-feed conveyor onto one of the live storage conveyor lanes, its presence at the end of the cross-feed conveyor actuates a limit switch 7-LS which closes a normally open contact 220 to sound a first alarm device 224. Under ordinary conditions when there is no stack of cases on limit switch 7-LS, a normally closed contact 226 of switch 7-LS remains closed to energize a coil 228 of a time delay control relay 7-CR. A normally open contact 230 of the time delay control relay 7-CR closes at a predetermined time after control relay coil 228 is energized.

A limit switch 2-LS is closed when the cross-feed conveyor reaches its returned position, thereby energizing a coil 232 of a control relay 2-CR. A normally open contact 234 of the control relay 2-CR is closed whenever control relay coil 232 is energized to thereby supply power to a coil 235 of a first time delay relay 1-TDR so long as the contact 230 of control relay 7-CR remains closed, indicating that no stack of cases is present at the end of the cross-feed conveyor. A normally open contact 236 of time delay relay 235 is closed after a predetermined time delay to supply power to a solenoid valve coil 237 of the cross-feed cylinder. This moves the piston rod of the cross-feed cylinder from its returned position to its forward position to provide a forward stroke of the cross-feed conveyor carriage 162.

A coil 238 of a control relay 3-CR is energized when the normally open contact 214 of control relay 1-CR is closed, thereby indicating that the cross-feed conveyor carriage 162 is in its forward position. A normally open contact 239 of control relay 3-CR is closed whenever control relay 3-CR is energized to thereby supply power to a solenoid valve coil 240 of an inter-lock cylinder (not shown). When actuated, the inter-

lock cylinder pushes a stack of cases from the in-feed conveyor 48 (see FIG. 1) onto the cross-feed conveyor. Control relay coil 238 of relay 3-CR is maintained in its energized condition through a closed contact 239A until a normally closed contact 242 of control relay 2-CR opens. This prevents the interlock cylinder from pushing a stack of cases onto the cross-feed conveyor when the cross-feed conveyor has reached its returned position.

When the code card in the top case of a stack of cases on the cross-feed conveyor actuates a respective one of the photo-electric cells 182, a corresponding contact 242 is closed to energize a coil 244 of a control relay 5-CR, but only if the normally closed contact 241 of control relay 2-CR is closed, indicating that the cross-feed conveyor is not in its fully returned position and has not actuated limit switch 2-LS. A normally open contact 246 of control relay 5-CR closes when coil 244 of relay 5-CR is energized to thereby supply power to a solenoid valve coil 248 of the stack transfer cylinder 184. When solenoid valve coil 248 is energized, the push-rod 186 of the stack transfer cylinder 184 pushes a stack onto the in-feed end of the live storage conveyor lane. However, solenoid valve coil 248 is energized only when contact 214 of control relay 1-CR is closed, indicating that the cross-feed conveyor carriage is in its fully forward position and actuating limit switch 1-LS. Furthermore, solenoid valve coil 248 is energized either when the normally closed contact 256 of limit switch 3-LS (described in detail below) is closed and a contact 249 of relay 5-CR is closed, indicating that no stack is positioned on limit switch 3-LS at the in-feed end of the live storage conveyor lane, or when the normally closed contact 290 of a limit switch 4-LS (described in detail below) is closed thereby indicating that the lane is not full of stacks and that there is a space in the lane for receiving the stack being transferred. If the normally closed contacts 256 of 3-LS and 290 of 4-LS are both open, this indicates that the lane may be full so the stack transfer cylinder does not actuate to push another stack into the lane. When the cross-feed conveyor carriage is in its returned position so as to close the normally open contacts of limit switch 2-LS, and thereby energize relay coil 232, power is supplied through the closed contact 234 of relay 2-CR to a solenoid valve coil 250 of the stack transfer cylinder 184 to move piston rod 186 to its retracted position.

When a stack of cases is transferred onto a live storage conveyor lane, it contacts triggering device 188, as previously described. This closes a normally open contact 252 of limit switch 3-LS. When contact 252 is closed, control relay coil 258 is energized to close a normally open contact 269 of control relay 4-CR to supply power to a solenoid valve coil 262 of the indexing cylinder 190. When solenoid valve coil 262 is energized, the piston rod 192 of the main indexing cylinder 190 moves to its forward position to provide a forward stroke of the live storage conveyor carriage 70 for pulling a stack of cases onto the conveyor track and at the same time advancing all stacks that have a space for receiving them. However, the indexing cylinder starts a forward stroke only if the cross-feed conveyor carriage is in its returned position with contact 234 of control relay 2-CR closed. Power is supplied to a solenoid valve coil 264 of the main indexing cylinder to move the piston rod 192 back to its returned position, but

only if normally closed contact 241 of the control relay 2-CR is closed, indicating that the cross-feed conveyor carriage has moved away from its returned position on limit switch 2-LS, after having waited out the closing of time delay relay contact 236.

A move-up selector switch 266 mounted on a control panel (not shown) adjacent to the accumulating area 36 has a rotary arm 268 adapted to be moved by an operator to a selected one of a number of positions, labeled A through F in FIG. 18. Each position of the switch corresponds to a particular live storage conveyor lane. When it is desired to accumulate stacks of cases side-by-side on a particular lane, rotary arm 268 is moved to the position which corresponds to the desired lane, and an off-on switch 270 is closed to energize control relay coil 258 of relay 4-CR to thereby supply power to solenoid valve coil 262 for a forward stroke of the main indexing cylinder 190. However, power is supplied to relay coil 258 only when a normally closed contact 271 of control relay 2-CR is closed, indicating that the cross-feed conveyor carriage has moved away from its returned position; and when control relay coil 258 is energized, its normally open contact 260 is closed supplying power to coil 262 when the cross-feed conveyor carriage arrives at its returned position causing contact 234 to close. This prevents the indexing cylinder from making a short stroke in the event the off-on switch 270 is closed during movement of the cross-feed cylinder. Indexing cylinder 190 continues to reciprocate once for each cycle of the cross-feed conveyor as long as switch 270 remains closed. Thus, stacks of cases on the lane are moved up and accumulated at the discharge end of the lane.

A load-out selector device 272 mounted on the control panel adjacent to the storage area 36 includes a ganged rotary switch 273 with a first rotary arm 274 and a second rotary arm 276. The arms of ganged rotary switch 273 are adapted to be moved by an operator to a selected position corresponding to the lane from which it is desired to discharge accumulated stacks onto out-feed conveyor 52. When a pushbutton 1-PB on the control panel is actuated, a coil 280 of a holding relay 1-HR corresponding to the position of the first arm 274 is energized to maintain a normally open contact 282 of the holding relay in a closed position. While contact 282 remains closed, power is supplied to a respective control relay coil 284 corresponding to the position of the second arm 276 to thereby close a normally open contact 286 of control relay 6-CR. When a solenoid valve coil 288 is de-energized, the piston rod 202 of the control spring carrier cylinder 200 extends forward to slide the control spring carrier bar 106 to its forward position. During the time that the contact 286 remains closed, power is supplied to relay coil 258 of relay 4-CR to continuously reciprocate the indexing cylinder 190 and thereby discharge stacks of cases onto out-feed conveyor 52. However, holding relay coil 280 is initially energized through normally open pushbutton 1-PB only when a normally closed contact 289 of the control relay 2-CR is closed, thereby indicating that the cross-feed conveyor carriage is away from its returned position; and when the control relay coil 258 is energized, its normally open contact 260 is closed, but the index cylinder forward coil 262 can only be energized when the cross-feed conveyor arrives at its returned position and closes limit switch 2-LS causing contact 234 of relay 2-CR to

close. This prevents the indexing cylinder 190 from making a short stroke in the event pushbutton 1-PB is closed while the cross-feed conveyor is in its returned position and while the time delay period for moving index cylinder 190 forward has partially elapsed.

When a stack of cases is positioned at the discharge end of a lane, it actuates limit switch 4-LS, as previously described. This opens the normally closed contact 290 and closes the normally open contact 292 when contacted by a stack of cases at the discharge end of the conveyor track. When contact 290 opens, it cuts off power to the solenoid valve coil 248 of the stack transfer cylinder 184 if contact 256 of the limit switch 3-LS is also open. This prevents the stack transfer cylinder from pushing a stack of cases onto the in-feed end of the live storage conveyor track when the conveyor track may be full. When contact 292 of switch 4-LS simultaneously closes, power is supplied to a solenoid valve coil 288 of control spring carrier cylinder 200 to retract the piston rod 202 of the control spring cylinder and thereby slide the control spring carrier bar to its retracted position, allowing the lugs 80 to drop down if sensing spring 90 is also depressed. This prevents the conveyor carriage 70 from discharging a stack of cases during the next forward stroke of the indexing cylinder. However, the control spring carrier bar is retracted only when a normally closed contact 298 of the control relay 6-CR remains closed, indicating that the load-out sequence of the conveyor has not been initiated.

A separate lock-out switch 300 located in a suitable position at the discharge end of each live storage conveyor is adapted to sense when a stack of cases is not properly discharged during the load-out sequence. For example, if a stack is twisted or not completely discharged, the lock-out switch 300 is closed. During the load-out sequence, contact 292 of the limit switch 4-LS is closed, a contact 301 of relay 6-CR is closed, and the normally open contact 286 of the control relay 6-CR is closed. Thus, closing of the lock-out switch 300 supplies power to the solenoid valve coil 288 of the control spring carrier cylinder 200 to retract the control spring carrier bar 106. This prevents a stack of cases from being pushed out against the improperly discharged stack. Closing of the lock-out switch 300 also supplies power through a closed contact 302 of relay 6-CR to a coil 303 of a second time delay relay 2-TDR which closes a normally open contact 304 of time delay relay 2-TDR to activate a second alarm device 306 after a predetermined time period to warn the operator of the improperly discharged stack.

The features of this invention have been described in the context of the embodiments of the invention which are presently preferred, and it is understood that many other variations and modifications can be made without departing from the scope of the invention. For example, conveyor track 68 could be modified as shown in FIG. 21 to include a series of rollers 310 in place of the wear strip 66 for supporting stacks of cases 32. Furthermore, channel member 74 could be modified as shown in FIG. 22 to include rollers 312 adapted to rest on the bottom of outer channel 62 to thereby permit the channel member 74 to reciprocate relative to the outer channel member 62.

The lug control spring and mounting block combination can be constructed as shown in FIGS. 23 through 25 to include a mounting block and spring holder 314 with an elongated centrally disposed notch 316 having

an upper surface 317 curved downwardly toward one end, and a vertically disposed slot 318 formed in the other end. A cooperating lug control spring 320 includes a vertically disposed end portion 322 with an inwardly turned marginal edge 324. Spring 320 is fastened to block 314 by sliding end portion 322 of the spring downwardly into slot 318 so the inwardly projecting edge 324 makes a snap fit with a cooperating notch 326 formed in the lower portion of the slot 318. In use, when the spring 320 is contacted by a cooperating engaging lug, the spring deflects downwardly into notch 316 and thereby substantially prevents bending stress from being exerted on the spring from the block. This form of the invention also permits ease of assembly because each lug control spring simply snaps into its cooperating spring holder and block 314. Assembly and construction costs also can be reduced by a spring holder and mounting block 328 shown in FIG. 26 which is preferably constructed in the form of a stamped metal clip having a pair of parallel elongated ribs 330 raised above the level of the carrier bar 106 by upwardly extending legs 332 at the ends of each rib. A separate outwardly extending marginal edge 334 is integral with the legs at each end of the clip, and an elongated centrally disposed notch 336 is formed in the clip between ribs 330 to define an upper surface 338 curved downwardly toward one end of the clip. A slit-like opening 340 is formed on the surface 338 adjacent to the other end of the clip for holding a cooperating lug control spring. The clip can be mounted on the carrier bar 106 by welding the marginal edges 334 to the upper surface of the bar, and sliding a molded plastic insert (not shown) into the opening 342 at the side of the clip. The insert provides rigidity for the clip, and a notch (not shown) can be formed in the lower edge of the insert below opening 340 to provide a snap fit for a cooperating lug control spring, such as spring 320, having an inwardly projecting edge 324. Alternatively, a block (not shown) having a configuration similar to the insert can be welded or otherwise bonded to the carrier bar 106, with the clip 328 making a tight friction fit over the block. As a further alternative, the clip can have an elongated opening through its center in place of curved upper surface 338, with a cooperating insert or block providing a curved upper surface similar to surface 338 of the clip.

FIGS. 27 through 29 show alternative means for fastening a lug pivot pin to channel member 74 to permit easy removal of pivot pins or engaging lugs without the need for special tools. FIG. 27 shows a pin retainer clip 324 formed from a piece of flat spring metal and having an upright clamping member 344, an upper edge portion 346 bent away from the top of clamping member 344, and an inner keeper portion 348 bent downwardly from the inner edge of upper edge portion 346. A downwardly opening groove 350 having an enlarged circular opening 352 is formed in the clamping member 344, and in use the upper edge portion 346 of the clip fits over the upper edge of channel member 74 so the outwardly projecting end portion of pivot pin 82 fits into the circular opening 352 in the groove 350. Preferably, an annular groove 354 is formed on the pivot pin adjacent to the outer wall of the channel member 74, and the clamping member 344 fits into the groove to tightly fasten the clip to the pivot pin. The keeper portion 348 of the clip has a downwardly opening groove 355 that fits over the pivot pin 82 adjacent to the inner

wall of the channel member. The keeper cooperates with clamping member 344 to prevent lateral movement of the pivot pin relative to the channel member. Alternatively, a retainer such as a spring wire clamp 356 shown in FIG. 29 can fit into a respective cooperating annular groove 354 formed in the pivot pin adjacent to each outer wall of channel member 74 to fasten the pin to the channel member and to prevent relative lateral movement of the pivot pin relative to the channel member. Both the clip 342 and the clamp 356 are easily removed from the pivot pin by simply prying upwardly with a screwdriver, needle-nosed pliers, or the like.

FIG. 30 shows an alternative engaging lug 358 for moving stacks of cardboard or wooden cases, for example, having no bottom rims against which the lug can be pushed to pull the stacks forward along the conveyor. Lug 358 has an upper surface portion defined by an angular insert 360 fastened to the front of the lug by a screw 362. Insert 360 has sharp laterally extending teeth 364 projecting upwardly from its upper surface. Alternatively, an angular insert 366 with sharp pointed teeth 368 on its upper surface can be fastened to lug 358, as shown in FIG. 31. Preferably, the angle δ between the horizontal plane and a line from the pivot point 370 of the lug through the frontal edge of either insert is maintained at 45° or slightly greater than 45°. In use, when engaging lug 358 is held in contact with the flat bottom portion of a case, the sharp teeth 364 and 368 dig into the bottom of the case as the channel member 74 moves forward. This causes the lug to rotate upwardly to an angle δ of about 60° which lifts the front of the case slightly off the conveyor track 68 and thereby allows the lug to move the case forward.

FIGS. 32 through 39 show a presently preferred embodiment of the lug-type accumulating conveyor of this invention, in which objects on a conveyor track 369 are moved by a sensing and engaging mechanism which includes a series of longitudinally spaced apart engaging lugs 370 mounted centrally between side walls 372 of a single reciprocating lug carriage channel 373 disposed between the parallel rails of conveyor track 369. The lug carriage channel rests on an elongated wear strip 374 disposed in the bottom of an upwardly opening outer channel 375 extending the length of the conveyor.

As shown best in FIG. 33, engaging lug 370 preferably is constructed from a sheet metal stamping 376 which can be mass produced at relatively low cost. The sheet metal stamping, in flat form, includes a pair of opposed substantially triangular side plates 377 interconnected by a rectangular bridge 378 having a forwardly projecting rectangular tab 380. The lug is formed by bending down the side plates at right angles to the bridge and bending the tab downwardly at an acute angle relative to the bridge to match the angular orientation of the front edges of the adjacent side plates. The edges of the tab are then rigidly secured to the side plates, say by welding, to hold the side plates in a fixed substantially parallel position relative to each other.

As shown best in FIG. 32, each engaging lug 37 is mounted to pivot on a transverse shaft 382 which extends through opposed openings 384 in the side plates of the lug and through opposite side walls 372 of channel 373. The pivot point of each engaging lug preferably is located at a point which makes the lug nose heavy. Thus, the lug is free to pivot under gravity to a

nose-down position shown in FIG. 32. In this position, a bottom tip 385 of each lug side plate rests against the upper surface of a transverse bottom 386 of channel 373.

The operation of the presently preferred sensing and engaging mechanism is understood best by referring to FIGS. 34 and 35, which show a series of engaging lugs 370 mounted on channel 373 in a longitudinally spaced apart fashion similar to the lugs in the conveyor system described above in FIGS. 1 through 31, except that lugs 370 are positioned behind the objects 32 carried on the conveyor track, and are controlled so that they push the objects along the track, rather than pulling them. I have found that such a system is more reliable and versatile than one in which they lugs pull the objects forward by engaging a downwardly projecting lip at the front of each object. For example, in a dairy plant milk cases are constantly subjected to rough treatment in which the lip at the bottom of a case often is broken or chipped. Consequently, a dairy plant conveyor which relies on the integrity of the bottom lip of the cases often can be jammed if the lip of a case is broken or chipped, because the engaging lug may experience difficulty in properly gripping the case.

The improved sensing and engaging mechanism shown in FIGS. 32 through 39 controls engaging lugs 370 by use of a series of longitudinally spaced apart elongated sensing arms 388 pivotally mounted to carriage channel 373. Preferably, each sensing arm is a steel rod bent into a profile which, when viewed from the side as in FIG. 34, includes a straight long front leg portion 390, a straight long rear leg portion 392, a substantially S-shaped bend 394 between the front and rear leg portions, a downwardly projecting nose 396 bent downwardly at an obtuse angle with respect to the front leg portion, and an upwardly turned tail 398 bent at a slight angle with respect to the rear leg portion. When viewed from above, as in FIG. 35, each sensing arm defines a substantially S-shaped offset 400 in an intermediate portion of the rear leg portion to provide clearance for the nose of another sensing arm located behind it, and a hooked tail end portion or extension arm 402 extending transversely above the tail end of the particular engaging lug the sensing arm is adapted to control.

Lug carriage channel 373 has a relatively wide clearance on both sides of each engaging lug, and the sensing arms are disposed in the clearance area at the sides of the engaging lugs in an alternating fashion, so that one lug will be controlled by an arm to its left, the next lug will be controlled by an arm to its right, etc.

A separate upright, elongated bar-shaped counterweight 404 is rigidly secured to the top of each rear leg portion 392 of the sensing arms. Preferably, the front end portion of each counterweight 404 is pivotally mounted to the shaft 382 in front of the lug to be controlled by the sensing arm on which the counterweight is mounted. The counterweights are positioned so each sensing arm is tail-heavy in its normal operation, and therefore free to pivot under gravity to a nose-up position.

During use, the sensing arms are adapted to pivot either nose-up or nose-down to move their transverse tail portions 402 down or up, respectively. When the tail portion 402 of a given sensing arm moves down, its respective engaging lug is pivoted to an operative nose-up position. Conversely, when the tail portion 402 of the

sensing arm moves up, it allows its lug to drop under gravity to an inoperative nose-down position.

As shown best in FIGS. 34 and 35, each sensing arm reaches forward to the space immediately ahead of the space occupied by the object to be moved by its corresponding engaging lug. This arrangement enables the engaging lugs to be operated so they push objects rather than gripping a front lip of the object and pulling it to the next space. In operation, when a given space on the conveyor track is not occupied, the tail-heavy sensing arm is normally operative to stay in a nose-up position which forces tail portion 402 of the arm downwardly against the tail of its corresponding engaging lug to raise the lug to an operative nose-up position. Thus, when the conveyor carriage is reciprocated, the engaging lug is in a position to push an object immediately ahead of it into the empty space sensed by its corresponding sensing arm.

Conversely, if a space on the conveyor track is occupied by an object, the object forces the nose of the sensing arm down and thereby raises its tail portion 402, which allows the sensing arm's corresponding engaging lug to drop under gravity to its normally inoperative nose-down position. Thus, when the conveyor carriage is reciprocated in this instance, the lug stays down and will not push any object located above it into an occupied space in front of the object.

Thus, continuous reciprocation of the conveyor carriage alternately forces the sensing arms to nose-up and nose-down positions, which thereby move objects along the conveyor track in a spaced apart relation, with an unoccupied space being present between each object. When the leading object reaches the end of the track, and alternate spaces behind it are filled continuously for the length of the track, continuous reciprocation of the carriage combined with feeding in of the objects at the infeed end of the track cause the sensing arms to progressively inactivate the engaging lugs and thereby allow objects to accumulate in an end-to-end relation along the length of the track.

After the objects have accumulated in such a manner along the conveyor track 369, all engaging lugs are in their inactivated nose-down position. Thereafter, some, or all, of the objects accumulated on the track can be discharged onto an out-feed conveyor 406 (FIG. 36) extending perpendicular to the longitudinal axis of conveyor track 369. As shown best in FIGS. 32 and 36, each engaging lug 370 includes a substantially C-shaped torsion spring 408 for use in raising the lugs to their operative position when discharging objects onto out-feed conveyor 406. Each spring preferably is made of relatively stiff strip metal. Each spring is disposed between side plates 376 of the lug, and is rigidly secured to the under side of bridge 378 by a screw 410 threaded into an opening 412 in the bridge. (The torsion springs are not shown in FIGS. 34 and 35 for clarity.)

An elongated control rail 414 is disposed centrally within channel 373 and rests on the upper surface of channel bottom 386. The width of the control rail is slightly narrower than the distance between the inner edges of the parallel side walls 376 of the engaging lugs. The control rail extends substantially the entire length of channel 373 and is movable relative to the channel and the lugs by suitable drive means (not shown). Separate longitudinally spaced apart lug control blocks 416 are secured to the upper surface of the control rail behind the control springs of the engaging lugs.

When it is desired to discharge the objects accumulated at the end of conveyor track 369, control rail 414 is moved forward to force the lug control blocks 416 into contact with the bottoms of the control springs 408 (as shown in FIG. 36) to override the instructions of sensing arms 388 (not shown in FIG. 36) and raise lugs 370 into their operative nose-up positions. Thereafter, continued reciprocation of the lug carriage channel automatically discharges objects 32, one per reciprocation, onto out-feed conveyor 406.

Out-feed conveyor 406 preferably is a lug-type conveyor which is substantially identical in operation to cross-feed conveyor 49 shown in FIGS. 15 and 16 above. As shown best in FIG. 36, the out-feed conveyor includes an upwardly opening outer channel 418 with outwardly extending and horizontally disposed upper marginal flanges 420 which support a pair of longitudinally extending and laterally spaced apart flat load support tracks 422. The bottoms of the objects 32 ride on load support tracks 422 as they are pushed along the out-feed conveyor. An upwardly opening elongated lug carriage channel 424 is disposed centrally within outer channel 418 and is adapted for reciprocating longitudinal movement in a manner similar to that of out-feed conveyor 52 described above. Lug carriage channel 424 rests on an elongated wear strip 426 supported by the bottom of outer channel 418. Engaging lugs 370 are pivotally mounted in a longitudinally spaced apart relation between the side walls of channel 424. A longitudinally movable control rail 427 is mounted centrally in the bottom of channel 424 and is disposed between the inner edges of the side walls 377 of the engaging lugs 370 in a manner identical to control rail 414. Control rail 427 carries separate longitudinally spaced apart lug spring control blocks 416 adapted to engage respective torsion springs 408 of the engaging lugs mounted on channel 424. Out-feed conveyor 406 contains no sensing arms such as sensing arms 388, because its purpose is not to accumulate objects, but to move them forward, one space at a time, along the length of the track 422 after the objects are discharged onto the out-feed conveyor.

During the forward stroke of the out-feed conveyor, control rail 426 is maintained in a forward position in which its lug spring control blocks 416 hold engaging lugs 370 in their operative nose-up positions. After an object is discharged onto the out-feed conveyor track, (between lugs 370 of the out-feed track), the out-feed conveyor channel 424 is reciprocated by first moving it forward so the engaging lugs push the objects on track 422 one space forward to clear the out-feed conveyor so it can receive the next object to be discharged by reciprocating channel 373. Out-feed conveyor channel 424 is then moved in a reverse direction to position the engaging lugs for the next forward stroke of the out-feed conveyor. (Prior to reciprocating channel 424 in its reverse direction, control rail 426 is moved to its rear position in which the control blocks are out of contact with the lug control springs so the lugs are able to drop under gravity to their normal nose-down positions). The accumulating conveyor carriage channel 373 and the outfeed channel 424 are continuously reciprocated in an alternating fashion until some, or all, objects on track 369 are discharged onto the outfeed conveyor. Thereafter, continued reciprocation of out-feed channel 424 moves the discharged objects down

the outfeed conveyor to the accumulating and shipping area 38.

FIGS. 37 through 39 show an improved cross-feed conveyor 430 and an improved stack transfer mechanism 432 for transferring objects from the cross-feed conveyor onto the accumulating conveyor track 369.

The stack transfer mechanism 432 includes a transverse rotatable shaft 434 extending through the side walls 372 of channel 373. The shaft is journaled for rotation in a pair of bearing bosses 435 welded to the inner edges of channel side walls 372. The opposite ends of the shaft 434 extend outwardly from the side walls of the channel, and each end carries a separate collar 436 set screwed to it. A pair of laterally spaced apart right and left transfer lugs 438 are welded to the outer edges of the two collars 436. Each transfer lug 438 has a wide central portion 439 mounted on shaft 434, a pointed nose 440 adapted to be raised above the top of track 369, and a pointed tail portion 442. A pair of outwardly extending lug rotation stops 444 are welded to the outer edges of channel side walls 372, and positioned so the tail portions of the right and left transfer lugs abut against the stop when the lugs are rotated to their nose up positions.

A transfer lug rotation arm assembly 446 is disposed at one end of shaft 434. The rotation arm assembly includes a collar 448 set screwed to shaft 434 adjacent the outer edge of the left transfer lug 438. A counterweight 450 is fitted on shaft 434, and is rigidly secured to the edge of collar 448 so the counterweight rotates with the shaft. A substantially L-shaped rotation arm 452 is rigidly secured to the counterweight so the arm rotates with shaft 434. Rotation arm 452 has a downwardly projecting leg 454 which is contacted by a linearly reciprocating piston arm 456 of an air cylinder 458 disposed below the rotation arm. When piston arm 456 is in its extended position (shown in FIG. 37) it forces leg 454 forward to pivot transfer lugs 438 to their nose-up positions so their noses 440 extend above the top of track 369. When piston arm 456 is retracted, the nose-heavy rotation arm drops to its normally nose-down position, under the influence of counterweight 450, to thereby pivot noses 440 of the transfer lugs below the top of conveyor track 369, as shown in FIG. 39.

In use, transfer lugs 438 transfer objects from cross-feed conveyor 430 onto an appropriate one of the live storage conveyor lanes 50 provided by tracks 369. Referring to FIG. 37, the improved cross-feed conveyor 430 is identical in operation to the outfeed conveyor 406 described above. The cross-feed conveyor includes an outer channel 460, and a pair of elongated laterally spaced apart, flat load support tracks 46 secured to the legs of the outer channel for supporting objects pushed along the cross-feed conveyor. A reciprocating lug carriage channel 464 holds a series of longitudinally spaced apart engaging lugs 370 adapted to push objects 32 along track 462. Lugs 370 are held in their operative positions by forward advancement of the control rail 414 which slides the lug spring control blocks 416 into contact with torsion springs 408 of the lugs in a manner identical to that described above for the out-feed conveyor. When the lugs are held in their operative nose-up positions, reciprocating movement of channel 464 moves objects disposed on cross-feed track 462 forward, one space at a time. When an object on track 462 reaches the entrance of a particular one of the storage

conveyor lanes 50 on which it is to be accumulated, air cylinder 458 is energized to extend its piston arm 456 and thereby rotate transfer lugs 438 into their nose-up positions shown in FIG. 37. Carriage channel 373 is then reciprocated so that during its forward stroke the transfer lugs will grip the front lip 78 of the object and pull it onto the conveyor track. If another object is disposed immediately in front of the object to be transferred, an engaging lug 370 mounted immediately in front of transfer assembly 432 pushed the object into the next unoccupied space in the manner described above. The lug immediately in front of transfer assembly 432 has a slightly modified tail design (as shown in FIG. 37) to provide clearance for the transfer assembly.

The cross-feed conveyor and out-feed conveyors are both capable of being manufactured at substantially lower cost than chain conveyors of the same length. Moreover, the lug type cross-feed conveyor is especially suitable for keeping track of the location of different objects conveyed on it. For example, in a dairy plant, stacks of cases containing different products can be fed along the cross-feed conveyor for storage on an appropriate ones of the storage lanes 50. A fixed number of forward strokes of the cross-feed conveyor moves a given stack of cases to a certain storage lane, so a simple countdown mechanism can be used to keep track of where each stack is located on the cross-feed conveyor. When a given stack reaches the lane where it is to be stored, transfer mechanism 432 is then simply activated to pull the stack of cases onto the appropriate storage lane. The transfer mechanism is also a substantial improvement over other known transfer devices, such as separate hydraulically operated pusher arms, which are relatively expensive to purchase and install and also more costly to operate and maintain.

FIGS. 40 and 41 show an alternate method of raising and lowering engaging lugs 370, in which control springs 408 are replaced by separate coiled torsion springs 466 mounted on each shaft 382. One end of each torsion spring has an elongated extention arm 468 which lies in a substantially horizontal plane and extends forward of the engaging lug pivot point. The other end of the torsion spring includes a downwardly extending lug position control arm 470 having a horizontally disposed leg 472 at its free end located so it can be engaged by a respective lug control block 416.

When objects are to be discharged onto out-feed conveyor 406, a forward stroke of control rail 414 moves lug control blocks 416 in the direction represented by the arrow in FIG. 41 and into contact with legs 472 of the torsion springs. This causes extention of arms 468 to pivot upward (in a clockwise direction shown in FIG. 41) to raise engaging lugs 370 to their operative nose-up positions. Thereafter, continued reciprocation of lug control channel 424 automatically discharges objects onto out-feed conveyor 406.

The advantage of using torsion springs 466 is that a relatively small amount of stress is placed on these springs when they are engaged by the control blocks. Moreover, they absorb energy well, and therefore do not put any excessive drag on the control rail during each forward stroke.

The engaging lugs 370 carried on out-feed conveyor 406 and cross-feed conveyor 430 also can include torsion springs 466 in place of lug control springs 408.

FIGS. 42 and 43 show a presently preferred method of mounting each shaft 382 to the side walls 372 of channel 373. In this form of the invention, opposing key-hole slots 474 are formed in the channel side walls at locations where each shaft is to be mounted. As shown best in FIG. 42, each key-hole slot includes a narrow vertically disposed opening 476 at the top of each channel side wall, and an enlarged rounded opening 478 below narrowed opening 476. A separate bushing 480 is mounted in the rounded opening of each key-hole slot. Each pair of opposed bushings has matching holes 482 for receiving the end portions of a respective lug shaft 382. The shaft makes a freely rotatable loose fit in the matching holes. Each shaft is restrained against lateral movement relative to the channel side walls by separate washers and cotter pins (not shown), or other suitable fastening means.

In use, in the event an engaging lug requires removal for repair, replacement, or the like, bushings 480 are simply removed from the key-hole slots, and the shaft and engaging lug are then free to be removed from the channel by lifting them up through the slot. Narrow opening 476 provides clearance for the end portions of shaft 383 to allow for removal of the engaging lug and shaft.

I claim:

1. In a live storage conveyor having a conveyor track, a reciprocating carriage extending adjacent to the track, and means for reciprocating the carriage to move objects in a forward direction along the track, an improved sensing and engaging mechanism comprising a series of longitudinally spaced apart engaging lugs pivotally mounted to the carriage, and separate longitudinally spaced apart movable sensing members mounted to the carriage for controlling the action of respective engaging lugs, each lug being mounted to the carriage to normally pivot under gravity to an inoperative position out of contact with objects on the conveyor track, each sensing member being a longitudinally extending, continuous arm having a front portion located forward of its corresponding engaging lug and a rear portion movable into and out of pressure contact with the engaging lug, each sensing member being mounted so its front portion is normally held above the conveyor track to sense an unoccupied space on the track while the rear portion thereof is being held in pressure contact with its corresponding engaging lug to raise the lug to its operative position to contact objects on the conveyor track when the carriage is moved forward, the sensing member further being operative such that its front portion will move downwardly when contacted by objects on the track to move the rear portion thereof away from the engaging lug and out of pressure contact therewith to allow the lug to pivot under gravity to its inoperative position.

2. Apparatus according to claim 1 in which the engaging lug, when maintained in its operative position, provides an upright engaging surface disposed above the conveyor track, and an elongated forwardly projecting nose below the engaging surface portion, the nose defining a lower surface portion for contact with the sensing member.

3. Apparatus according to claim 2 in which the sensing member comprises a torsion spring, a portion of which is curved convex upwardly so as to contact objects disposed on the conveyor track above it.

4. Apparatus according to claim 1 in which the engaging lug has a tail portion located to the rear of its pivot point; and in which the rear portion of the sensing member provides a transverse extension arm adapted to pivot into and out of pressure contact with the tail portion of the lug when the forward portion of the sensing arm pivots above and below the conveyor track, respectively.

5. Apparatus according to claim 2 in which the engaging lug has a tail portion located to the rear of its pivot point, and in which the nose of the lug is arranged so it rests on the bottom of the conveyor carriage when the lug pivots to its inoperative position so as to prevent the tail portion of the lug from striking objects disposed on the conveyor track above it.

6. Apparatus according to claim 1 in which the engaging lug is mounted to the carriage by a transverse pivot pin secured to the carriage at a point such that the angle between a horizontal plane through the pivot pin and a line from the pivot pin through the point of engagement between the object and the engaging lug is at least about 45°.

7. Apparatus according to claim 1 in which separate longitudinally spaced storage locations are defined along the track, and a separate engaging lug is located to the rear of each storage location, and in which each sensing member extends in a forward direction from its corresponding engaging lug to the vicinity of the lug associated with the storage location located two spaces forward of the location associated with said corresponding engaging lug so that the sensing member will sense substantially the entire length of the storage location located in front of the object positioned in the storage location associated with said corresponding engaging lug.

8. Apparatus according to claim 1 including stop means disposed on the carriage below the engaging lug for limiting pivotal movement of the engaging lug away from the direction in which the objects are to be moved.

9. Apparatus according to claim 1 in which each sensing member extends adjacent to a respective outer longitudinally extending edge of its corresponding engaging lug, and includes a hooked end portion extending over a tail end portion of the lug to move into and out of pressure contact with the tail end portion of the lug when the forward portion of the sensing arm pivots above and below the conveyor track, respectively.

10. Apparatus according to claim 1 in which the conveyor carriage includes an upwardly opening, slidably, elongated channel member mounted in association with the conveyor track; and in which the engaging lugs are pivotally mounted to the channel member, and the sensing members are mounted to the channel member; and further including a channel member actuator for reciprocating the channel member relative to the track, whereby when each engaging lug is in its operative position, forward movement of the channel member actuator moves the lug into contact with the bottom of an object disposed on the conveyor track and forces the object forwardly along the track.

11. Apparatus according to claim 10 including an elongated control rail disposed within the channel member; means for moving the control rail relative to the channel member between a first position and a second position; and a series of spaced apart lug position control means mounted at locations on the control rail

for permitting pivotal movement of the engaging lugs to their inoperative position when the control rail is in its first position, and to maintain the lugs in their operative position, preventing movement to their inoperative position, when the control rail is in its second position.

12. Apparatus according to claim 11 in which the lug position control means includes separate control springs mounted adjacent to the bottom surface of the engaging lugs, each control spring having an end portion held in contact with the bottom of a respective lug, the end portion of the control spring being movable from the rear of the lug pivot point to the front of the lug pivot point as the control rail moves from its first position to its second position, respectively.

13. Apparatus according to claim 11 in which the lug position control means comprises a separate control spring carried by each engaging lug, and separate control spring actuating members carried by the control rail and positioned such that they are forced into pressure contact with corresponding control springs to raise the lugs when the control rail is moved to its second position, and such that they move out of pressure contact with the control springs to allow each lug to drop under gravity to its inoperative position when the control rail is moved to its first position.

14. Apparatus according to claim 11 including an out-feed conveyor at the discharge end of the conveyor track for receiving objects discharged from the conveyor track, means for maintaining the control rail in its second position, and means for continuously reciprocating the channel member actuator when the control rail is in its second position so as to discharge objects from the conveyor track onto the out-feed conveyor.

15. A conveyor system comprising a reciprocating carriage extending adjacent to a conveyor track for moving objects in a forward direction along the track, means for reciprocating the conveyor carriage, a sensing and engaging mechanism on the carriage for controlling the movement of objects along the conveyor track, the sensing and engaging mechanism including a series of longitudinally spaced apart engaging lugs mounted along the carriage, means for mounting each engaging lug to the carriage to pivot relative thereto, separate lug control means mounted on the carriage to contact corresponding engaging lugs to move each lug from an operative position, in which the lug is in a raised position to contact the bottoms of objects on the conveyor track, to an inoperative position, in which the lug is out of contact with the objects; and wherein the conveyor track has an in-feed end and further including a cross-feed conveyor at the in-feed end of the conveyor track for carrying objects to be transferred onto the conveyor track, and an in-feed transfer system for moving objects from the cross-feed conveyor onto the in-feed end of the conveyor track, the in-feed transfer system including selectively operable means arranged to be actuated for transferring an object from the cross-feed conveyor onto the conveyor track, indexing means activated in response to the presence of a particular object on the cross-feed conveyor, and means for actuating the transfer means in response to activation of the indexing means, the transfer means including an engaging lug mounted on the in-feed end of the conveyor carriage to normally pivot under gravity relative to the carriage to an inoperative position in which the lug is out

of contact with objects on the in-feed end of the conveyor track, the actuating means being movable in response to activation by the indexing means to raise the engaging lug from its inoperative position to an operative position in which it will contact an object at the in-feed end of the conveyor track and transfer the object onto the conveyor track when the carriage is reciprocated in a forward direction.

16. Apparatus according to claim 15 including sensing means actuated when the conveyor track is completely filled with objects, and disabling means activated in response to actuation of the sensing means for preventing the in-feed transfer system from moving objects onto the conveyor track.

17. Apparatus according to claim 15 in which the cross-feed conveyor includes a cross-feed track; a reciprocating cross-feed carriage cooperating with the cross-feed track for moving objects in a forward direction along the cross-feed track; a series of spaced apart cross-feed engaging lugs mounted along the cross-feed carriage and adapted to pivot from an operative position, in which each lug contacts the bottom of objects on the cross-feed conveyor track, to an inoperative position, in which the lug is out of contact with the objects, and stop means secured to the cross-feed conveyor carriage below the cross-feed engaging lugs and arranged to normally maintain the cross-feed engaging lugs in their operative position during each forward stroke of the carriage, the stop means being movable relative to the lugs to permit the cross-feed engaging lugs to pivot to their inoperative position during each return stroke of the cross-feed carriage.

18. Apparatus according to claim 15 in which the engaging lug at the in-feed end of each conveyor track includes a rotation arm rigidly attached to the lug such that movement of the rotation arm between first and second positions will pivot the lug between its inoperative and operative positions, respectively, and in which the actuating means includes a slidable piston which is movable in response to activation of the indexing means to engage the rotation arm and move it to its second position which, in turn, raises the lug to its operative position, the piston arm also being movable in response to activation of the indexing means to move out of engagement with the rotation arm to allow it to move to its first position which, in turn, allows the engaging lug to drop under gravity to its inoperative position.

19. A live storage conveyor comprising:
 a. a conveyor track having parallel rails for supporting objects to be conveyed;
 b. a conveyor carriage cooperating with the conveyor track for moving objects in a forward direction along the track, the conveyor carriage including an elongated upwardly opening channel member extending parallel to the rails of the track and adapted to move relative thereto;
 c. drive means for reciprocally moving the channel member relative to the conveyor track;
 d. a series of longitudinally spaced apart engaging lugs pivotally mounted to the channel member, each lug being mounted to normally pivot under gravity to an inoperative position in which it is out of contact with objects on the conveyor track; and
 e. a series of longitudinally spaced apart movable sensing members disposed within the channel member, each sensing member being associated

with a respective engaging lug and being a longitudinally extending, continuous arm having a front portion located forward of its respective engaging lug and a rear portion located so it is movable into and out of pressure contact with its respective engaging lug, each sensing member being mounted so its front portion is normally held above the conveyor track to sense an unoccupied space on the track while the rear portion of the sensing member is being held in pressure contact with the engaging lug to raise the lug to its operative position to contact objects on the conveyor track when the conveyor carriage is moved in a forward direction, each sensing member further being operative such that its front portion will move downwardly when contacted by objects on the track to move the rear portion thereof away from the engaging lug and out of pressure contact therewith to allow the lug to pivot under gravity to its inoperative position.

20. Apparatus according to claim 19 including means attaching each sensing member to the channel member, and in which each sensing member pivots relative to the channel member about a transverse axis through its respective attaching means, each sensing member being normally operative to pivot its forward portion above the conveyor track to sense objects on the track.

21. Apparatus according to claim 19 in which each engaging lug has a tail portion located to the rear of its pivot point; and in which each sensing member is pivotally mounted to the carriage, and the rear portion of the sensing member provides a transverse extension arm adapted to pivot into and out of pressure contact with the tail portion of its respective engaging lug when the forward portion of the sensing arm pivots above and below the conveyor track, respectively.

22. Apparatus according to claim 21 in which each sensing member has an intermediate portion which extends in a forward direction past the engaging lug located immediately in front of the lug which the sensing member is adapted to control, so the forward portion of the sensing member will sense objects located in the space immediately forward of the space associated with the lug which the sensing member is adapted to control.

23. Apparatus according to claim 22 in which alternating ones of said sensing members extend along one side of their respective engaging lugs, and the remaining alternating sensing members extend along the opposite side of their respective engaging lugs.

24. Apparatus according to claim 19 in which each engaging lug includes downwardly depending laterally spaced apart side walls, and a downwardly extending control spring between the side walls; and including a movable elongated control rail disposed in the channel and extending under the engaging lugs and the control springs thereof, means for moving the control rail relative to the channel member between a first position and a second position, and a series of longitudinally spaced apart lug position control members carried on the control rail, each lug position control member being arranged to move in and out of pressure contact with a respective one of the control springs to permit pivotal movement of the engaging lugs to their inoperative positions when the control rail is in its first position, and to maintain the lugs in their operative positions, preventing movement of the lugs to their inoperative positions, when the control rail is in its second position.

25. In a live storage conveyor having a reciprocating carriage extending adjacent to a conveyor track, and means for reciprocating the carriage to move objects in a forward direction along the track, an improved sensing and engaging mechanism comprising a series of longitudinally spaced apart engaging lugs pivotally mounted to the carriage so each lug normally pivots under gravity to an inoperative position in which it is out of contact with objects on the conveyor track; a movable elongated lug position control rail disposed below the engaging lugs; means for longitudinally reciprocating the lug position control rail independently of contact with the objects on the track and relative to the engaging lugs so the control rail moves between a first position and a second position; and a series of longitudinally spaced apart lug position control members carried on the control rail, each lug position control member corresponding to a respective one of the engaging lugs, the lug position control members being located on the control rail so that they move into or out of pressure contact with the engaging lugs when the control rail moves to its first or second position, respectively, the lug position control members being moved into pressure contact with the lugs to maintain the lugs in an operative position, above the conveyor track, so the engaging lugs will contact the objects disposed thereon, when the control rail is in its first position, the lug position control members being moved out of pressure contact with the lugs to permit movement of the engaging lugs to their inoperative position when the control rail is in its second position.

26. Apparatus according to claim 25 in which each lug position control member is positioned adjacent to the bottom of a respective one of the engaging lugs so the members will be forced into contact with the engaging lugs, each member having a working end portion movable between the rear of the lug pivot point and the front of the lug pivot point as the lug position control rail moves between its first position and its second position, respectively.

27. Apparatus according to claim 25 including a separate lug position control spring carried by each engaging lug forward of its pivot point, and in which each position control member is movable into and out of pressure contact with a respective control spring to pivot the lug from its operative to its inoperative position, respectively.

28. A live storage conveyor system comprising an elongated conveyor track for supporting objects to be conveyed; a reciprocating carriage extending adjacent to the track; means for reciprocating the carriage for moving objects in a forward direction along the track; a series of longitudinally spaced apart engaging lugs mounted to pivot about corresponding transverse axes along the carriage, each lug being mounted to pivot from an operative position, in which the lug contacts objects disposed on the conveyor track, to an inoperative position, in which the lug is out of contact with the objects; a separate control arm carried on each engaging lug forward of its pivot axis; and a separate movable lug position control member located adjacent to each engaging lug, the lug position control members being movable in unison relative to the engaging lugs between a first position and a second position, each lug position control member being movable to the first position thereof for pressure contact with a corresponding one of the control arms to pivot the engaging lugs to

their operative position in unison so they will force objects forwardly along the track when the conveyor carriage makes a forward stroke, the lug position control members also being movable to their second position where they are out of pressure contact with their respective control arms for allowing the engaging lugs to pivot to their inoperative positions.

29. Apparatus according to claim 28 in which the conveyor carriage includes a slidable control rail disposed below the engaging lugs, the control rail being movable relative to the series of engaging lugs, and means for securing the lug position control members to the control rail in longitudinally spaced apart relation, whereby movement of the control rail moves the lug position control members in unison into contact with the control arms to raise the engaging lugs and maintain them in their operative position.

30. Apparatus according to claim 28 in which each engaging lug is mounted to the carriage to normally pivot under gravity to its inoperative position when its corresponding lug position control member moves out of pressure contact with the control arm thereof.

31. In a live storage conveyor having a reciprocating carriage extending adjacent to a conveyor track, and means for reciprocating the carriage for moving objects in a forward direction along the track, an improved sensing and engaging mechanism comprising a series of engaging lugs mounted in longitudinally spaced apart relation along the conveyor carriage, each engaging lug being mounted to pivot from an operative position, in which the lug contacts the bottoms of objects on the conveyor track, to an inoperative position, in which the lug is out of contact with the objects, a separate movable sensing member for controlling the action of each engaging lug, each sensing member having one end secured to the conveyor carriage forward of the corresponding engaging lug, the other end of each sensing member being normally operative to contact its corresponding engaging lug to urge it into its operative position, each sensing member normally projecting above the plane of the conveyor track when no objects are present above them on the track for sensing the pressure of objects on the track, each sensing member also being movable downwardly when contacted by objects on the track above it to break the contact with its corresponding engaging lug and enable the lug to pivot to its inoperative position, and means for pivoting the engaging lugs to their operative positions independently of the control provided by the sensing members to override the normal operation of the sensing members.

32. Apparatus according to claim 31 in which said other end of the sensing member releasably contacts the engaging lug, and in which the lug pivoting means includes a slidable bar below the lugs, means for moving the bar relative to the conveyor track between a first position and a second position, and a series of lug position control members spaced apart along the length of the bar and arranged to permit corresponding engaging lugs to pivot to their inoperative position when the bar is in its first position, and to maintain the respective engaging lugs in their operative position, preventing movement to their inoperative position, when the bar is in its second position.

33. Apparatus according to claim 31 in which the lug position control member includes a horizontally disposed leaf spring adjacent to the bottom surface of the

engaging lug, the leaf spring having an end portion held in contact with the bottom of the lug, the end portion of the control spring being movable from the rear of the lug pivot point to the front of the pivot point as the bar moves from its first position to its second position, respectively.

34. In a live storage conveyor having a reciprocating carriage extending adjacent to a conveyor track, and means for reciprocating the carriage for moving objects in a forward direction along the track, the conveyor carriage including a pair of parallel, slidably elongated channel members adjacent to the track, an improved sensing and engaging mechanism comprising a series of spaced apart engaging lugs mounted on each channel member, each engaging lug being mounted to pivot from an operative position, in which an upper surface portion of the lug contacts the bottoms of objects on the conveyor track, to an inoperative position, in which the upper surface portion is out of contact with the objects; a series of spaced apart sensing springs mounted on each channel member for controlling the action of corresponding engaging lugs mounted thereon, each sensing spring having one engaging lug, the other end of the sensing spring being normally operative to contact its corresponding engaging lug to urge it into its operative position, each sensing spring also being positioned normally above the plane of the conveyor track so it will flex downwardly when contacted by objects on the track above it, whereby contact between the lug and the sensing spring is broken to permit the lug to pivot to its inoperative position; a channel member actuator for reciprocating the channel members together relative to the track, whereby when the engaging lugs are in their operative position, forward movement of the channel member actuator moves the lug upper surface portions into contact with the bottoms of objects disposed over the conveyor track and forces the objects in a forward direction along the track, an elongated control spring carrier bar disposed within the lower portion of each channel member; carrier bar actuator means for moving each control spring carrier bar relative to its respective channel member between a first position and a second position; and a lug control spring secured to each carrier bar arranged to both permit pivotal movement of each lug to its inoperative position when the carrier bar is in the first position, and to maintain the lugs in their operative position, preventing movement to their inoperative position, when the carrier bar is in its second position.

35. Apparatus according to claim 34 wherein each lug control spring includes a horizontally disposed leaf spring adjacent to the bottom surface of the engaging lug, the leaf spring having an end portion held in contact with the bottom of the lug, the end portion of the control spring being movable from the rear of the lug pivot point to the front of the lug pivot point as the carrier bar moves from its first position to its second position, respectively.

36. Apparatus according to claim 34 wherein each lug control spring includes an upwardly extending leaf spring having an upper end portion held in contact with the bottom of the engaging lug, the upper end portion being movable from the rear of the lug pivot point to the front of the lug pivot point as the carrier bar moves from its first position to its second position respectively.

37. Apparatus according to claim 34 including an out-feed conveyor at the end of the conveyor track, means for maintaining the control spring carrier bar in its second position, and means for continuously reciprocating the channel member actuator so as to discharge objects from the conveyor track onto the out-feed conveyor.

38. Apparatus according to claim 34 wherein the carrier bar actuator means comprises a separate double-acting cylinder mounted on each channel member, each cylinder having a reciprocating piston rod secured to a respective control spring carrier bar.

UNITED STATES PATENT OFFICE
CERTIFICATE OF CORRECTION Page 1 of 2

Patent No. 3,826,349 Dated July 30, 1974

Inventor(s) CLARENCE H. STEVENSON, III

It is certified that error appears in the above-identified patent and that said Letters Patent are hereby corrected as shown below:

[76] "308" should read -- 303 --.

Col. 8, line 33, "areas 36" should read -- area 36 --.

Col. 9, line 17, "oeprate" should read -- operate --.

Col. 13, line 31, "swwtch" should read -- switch --.

Col. 14, line 23, "coil 12" should read -- coil 212 --.

Col. 15, line 5, "242" should read -- 241 --;

line 35, "(described" should read -- (described --;

line 47, "pstion" should read -- piston --;

line 54, "269" should read -- 260 --.

Col. 19, line 61, "37" should read -- 370 --.

Col. 22, line 24, "movemement" should read -- movement --;

line 39, "no sensing aims" should read -- no sensing
arms --;

Col. 23, line 19, "trail" should read -- tail --;

line 46, "coross--" should read -- cross- --;

line 53, "tracks 46" should read -- tracks 462 --.

Col. 24, line 23, delete "an".
